UNITED STATES PATENT OFFICE.

BARRY IVOR AND JOHN S. WARD, OF CHICAGO, ILLINOIS.

FORCE-FEED LUBRICATOR.

SPECIFICATION forming part of Letters Patent No. 784,069, dated July 21, 1903.

Application filed February 27, 1902. Renewed December 15, 1902. Serial No. 135,325. (No model.)

To all whom it may concern:

Be it known that we, BARRY IVOR and JOHN S. WARD, citizens of the United States, residing at Chicago, in the county of Cook and State of Illinois, have invented certain new and useful Improvements in Force-Feed Lubricators, of which the following is a specification.

This invention relates to improvements in that class of lubricators or small pumps employed for forcing oil to any part or parts that it is desired to have constantly and uniformly lubricated; and it consists in certain peculiarities of the construction, novel arrangement, and operation of the various parts thereof, as will be hereinafter more fully set forth and specifically claimed.

The objects of our invention are to provide a lubricator which shall be compact in form, positive, direct, and uniform or even in operation, and so constructed that one or more pumps may be supplied with oil by the same reservoir and may be operated by the same driving mechanism.

Another object is to so construct and arrange the different parts of the apparatus that the oil-reservoir will be located near and usually above the steam-engine used for operating the pumps, thus keeping the oil warm by means of the heat from the engine, so that it will flow freely.

A further object is to provide means for automatically lubricating the frictional parts of the apparatus and also to indicate the quantity of oil being pumped as well as the movement of the driving-shaft.

Still another object is to provide means for forcing oil from the reservoir by means of a hand-pump.

Other objects and advantages of the invention will be disclosed in the subjoined description and explanation.

In order to enable others skilled in the art to which our invention pertains to make and use the same, we will now proceed to describe it, referring to the accompanying drawings, in which—

Figure 1 is a front view, partly in section and partly in elevation, of a lubricator embodying our invention. Fig. 2 is a view, partly in section and partly in elevation, taken on line 2 2 of Fig. 1 looking in the direction

indicated by the arrows, but showing the casing over the driving-gear removed. Fig. 3 is a view in elevation of a portion of the driving-shafts, illustrating the clutch mechanism thereon. Fig. 4 is a sectional view thereof, taken on line 4 4 of Fig. 1, looking in the direction indicated by the arrows. Fig. 5 is a vertical sectional view of the upper portion of one of the pumps, showing the construction of the oil-indicator thereon. Fig. 6 is a sectional view, taken on line 6 6 of Fig. 1, of the brake, showing it applied to the driving-shaft. Fig. 7 is a face view of the dial-indicator used to indicate the movement of the driving-shaft. Fig. 8 is a central vertical sectional view of the hand-pump and a portion of its discharge-pipes, and Fig. 9 is a longitudinal sectional view of the steam-engine used for operating the pumps.

Like numerals refer to similar parts throughout the different views of the drawings.

The numeral 15 represents the bracket used for supporting the casing or main frame 16, which bracket may be secured to a suitable support by means of bolts passing through openings 17 in its top and bottom. The casing or main frame 16 is preferably rectangular in shape and may have its front portion 80 closed by means of a door, which may be fastened by means of a seal, thus preventing access to and tampering with the adjusting devices of the lubricator. The lower portion of the main frame or casing 16 is formed with 85 a number of receptacles 18 to form oil-wells for lubricating certain parts of the machine. The casing 16 is preferably provided with a horizontal partition 19, on which is supported the steam-engine 20, used for operating the pump, and which engine may be of the ordinary or any preferred construction; but as we do not claim anything new in the engine itself we will describe such parts thereof only as will be necessary for the proper understanding of the operation of our apparatus. This engine consists of a cylinder 21, a piston 22, and a reciprocating piston-rod 23, with the necessary valves, ports, and packing to render it operative. Located on the 90 upper portion of the casing or main frame 16 is the oil-reservoir 24, which is provided with a supply-pipe 25, having at its upper end a removable plug or cap 26 to close the

same. One end of the reservoir is provided with a sight-gage 27, of the ordinary construction, used to indicate the quantity of oil contained therein. The front lower portion 5 of the reservoir is preferably provided with an offset 28 for the reception of a portion of the pumps, as will be presently explained. Horizontally journalled in the lower portion 10 of the casing or main frame 16, just above the wells 18 therein, are the driving-shafts 29 and 30, the latter being used as an auxiliary shaft when it is desired to operate all of the pumps. One end of the shaft 29 extends through the main frame and is screw-threaded, 15 as shown in Fig. 1 of the drawings. Located on the screw-threaded portion of the shaft 29 is a ratchet-wheel 31, which rotates with said shaft, and loosely mounted (and preferably on ball-bearings 32) on the shaft outside of 20 the ratchet-wheel is a beveled gear 33, which is preferably of the mutilated type—that is, it preferably has portions only of its face provided with beveled gear-teeth; but a complete beveled gear may be employed. This gear 25 is provided on its periphery with flanges 34, to each of which is pivotally secured a pawl 35, which are held in engagement with the ratchet-wheel by means of springs 36, as is shown in Fig. 2 of the drawings. Placed 30 over the ratchet-wheel 31 and gear 33 and secured to the end of the main frame 16 is a casing 37, which will exclude dust and has on its face a scale or graduate marks 38, used in connection with the pointer 39, fixed on the 35 outer end of the driving-shaft 29 to indicate the movement of the driving-shaft and the ratchet-wheel, which is fixed thereon. Fixed to the shaft 29, within the casing 16, is a collar 40, against which impinges a brake-shoe 41, which is provided with a headed stem 42, located in a tube 43, extending through the front part of the casing or main frame. The outer end of this tube is internally screw-threaded to receive a screw 44, between the 45 inner end of which and the head of the stem of the brake-shoe is located a spring 45 to keep said shoe in contact with the collar 40 on the driving-shaft. Fixed on the end of the shaft 30, or auxiliary shaft, adjacent to the shaft 29, is a collar 46, which is provided with a pin 47 to engage an opening 48 in the collar 49, which is slidably mounted on the shaft 29, with means to prevent turning on the same, and is provided with an annular 55 groove 50 for the reception and operation of rollers 51, journalled on the ends of the yoke 52, which has secured to one of its ends a lever 53, which is fulcrumed on the front portion of the casing or main frame. Enough 60 space is left between the walls of the groove 50 and the rollers 51 to allow them to properly coöperate with said walls when the lever 53 is turned on its fulcrum to shift the position of the slideable collar. Secured to the outer surface 65 of the casing 16 is a segment 54, which has notches 55 to receive the end of the spring-actuated grip-rod 56, which is pivoted to the

lever 53, as shown in Fig. 4 of the drawings. By turning the lever 53 on its fulcrum it is apparent that the collar 52 will be slid on the driving-shaft, so as to connect it or disconnect it with the collar 46, thus coupling the shafts 29 and 30 together or uncoupling them, as desired.

In Fig. 1 of the drawings we have shown 75 the apparatus as having four pumps to be operated by the steam-engine, two of which, 57 and 58, are operated by the main shaft 29 and the other two, 59 and 60, are operated by the auxiliary shaft. Between the pair of pumps 80 57 and 58 and between the pair of pumps 59 and 60 is located a vertical guide-piece 61 or bearing for the rods 62, and said guide or bearing pieces are formed at their upper ends with cups 63 for oil for said rods. The lower 85 end of each of these rods is screwed into a suitable socket 64 on a band 65, which surrounds an eccentric 66, secured by means of set-screws 67 or otherwise to one of the main driving-shafts at a point below and between 90 each pair of pumps. These pumps are of the same construction, and each consists of a vertical cylindrical portion 68 and a horizontal portion 69, which extends rearwardly and is secured to the front portion of the offset 28 95 of the reservoir by means of bolts 70. The lower portion of the cylindrical part 68 is formed with a stuffing-box 71, in which is suitable packing 72, and a gland or follower 73, surrounding the piston 74, which extends into 100 the cavity 75 of the pump and has on its lower portion an annular shoulder 76, against which the adjustable cross-bar 78 may rest, as will be presently explained. The upper portion 105 of the cylindrical part 68 is internally screw-threaded to receive the screw-threaded portion of a plug or cap 79, which is provided with a valve-chamber 80 and outlet-openings 81. Located in the valve-chamber 80, so as to close the channel 75, is a ball-valve 82. Extending horizontally from the front outer portion of the cylindrical part 68, through the cavity or oil-chamber 75 thereof, and into the horizontal portion 69 is an opening 83, which is closed by means of a screw-plug 84 and 115 85, which forms the horizontal valve-chamber 85, in which is located a ball-valve 86, which opens and closes the port 87 when the piston 74 is retracted and advanced. The valve-chamber 85 communicates with the oil-chamber 120 75 through ports 88 in a plug located in the outer end of the chamber 85, and the port 87 has communication with the valve-chamber 89 in the horizontal portion 69, said valve-chamber 89 being formed of a hollow 125 and open screw-plug 90, secured into a suitable opening in said horizontal portion. The valve-chamber 89 is provided with a ball-valve 91 to close the port 92, which communicates with the pipe 93, opening into the reservoir. 130

The lower portion of the pipe 93 is formed with an opening 94, which is closed by means of a plug 95, and which opening is for the

purpose of giving access to the valve-chamber 89 in order to place the screw-plug 90 and valve 91 therein. Located on the upper end of the plug or cap 79 is a tubular piece 96, to the upper end of which is connected one end of an oil-pipe 97, which may lead to any suitable point or part to be lubricated. Extending horizontally from the tubular piece 96 at about its middle is an extension 98, which is hollow and has an upwardly-extending arm 99, provided with a scale 100. Located in the opening of the extension 98 is a piston-rod 101, which is provided on its outer portion with enlargements 102 to act on the lower end of the pointer 103, which is pivotally secured to the arm 99 and is used in connection with the scale 100 to indicate the quantity of oil that is being forced through the tubular piece 96 and oil-pipe. The upper end of the tubular piece 96 is provided with a spring-pressed ball-valve 104 to normally close the opening in the tubular piece. By taking hold of the knob or thumb-piece with the hand on the outer end of the rod 101 and pressing it inwardly to the position shown in Fig. 5 it is apparent that as the oil is forced through the tubular piece 96 the piston-rod will be forced outwardly, thus causing one of the projections 102 to impinge the lower end 30 of the pointer 103 and to indicate on the scale 100 the rate of stroke of the pump-piston. The lower portion of each of the pistons 74 is screw-threaded to receive the jam-nuts 105 and the wing-nuts 106, used for removably connecting the cross-bar 78 to the piston-rods, as is clearly shown in Fig. 1 of the drawings. The cross-bar 78 may be adjustably secured to the rod 62 by means of a set-screw 107 passing through its central portion, and a nut 40 108, located on the rod 62, may be used for tightening the same in the socket 64 of the band 65 on the eccentric.

The cross-bars 78 are each provided near their ends with vertical slots, as shown, to 45 allow them to engage the piston-rods 74 by turning them on the rods 62 and without removing the nuts 105 and 106, as is apparent.

Secured to the outer end of the piston-rod 23 by means of a collar 109 and a set-screw 50 110 is a cross-head 111, having a slot 112, in which is adjustably secured, by means of nuts 113 and 114, a bolt 115, which has on its end a head 116 and passes through a slot 117 in a crank 118, which is secured on the end of a 55 shaft 119, journaled, preferably, in ball-bearings 120 on the lower portion of the main frame and at right angles to the main driving-shaft. Mounted on the shaft 119 is a beveled gear 121, which meshes with the beveled gear 33 on the driving-shaft. Communicating through a pipe 122 with the rear portion of the reservoir is a hand-pump 123, which is provided at one of its ends with a stuffing-box 124 and a gland or follower 125, 65 surrounding the piston-rod 126, which has on its outer end a hand-wheel 127 and on its inner end a piston 128 to operate in the cavity

129 of the pump-cylinder, which channel or cavity communicates with the oil-chamber 130, which is closed by means of a screw-cap 7c 131 on the opposite end of the pump-cylinder from that on which the gland is located. Communicating with the lower portion of the oil-chamber 130 and with the pipe 122 is a ball-valve 133 to open and close the same. Secured on the upper portion of the pump-cylinder 123 is a piece 134, having a valve-chamber 135, communicating with the upper portion of the oil-chamber and also with the 8c branch pipes 136, to each of which may be secured a pipe 137, leading to any desired point or part to be lubricated; but in the present instance we have shown the pipe 137 provided with a shut-off valve 138 and communicating with one of the pipes 97, leading from the engine-pumps.

From the foregoing and by reference to the drawings it will be clearly seen and readily understood that by the reciprocation of the 9c piston-rod 23 of the engine and its connection with the shaft 119 said shaft and the gear 121 which it carries will be rocked back and forth, thus imparting an oscillatory motion to the gear 33, which by means of its 95 pawls 35 will cause the ratchet-wheel 31 and the driving-shaft 29 to be intermittently rotated, in which operation the piston-rods 74 of the pumps will be intermittently reciprocated by reason of their connection through 100 the cross-bar 78 with the rod 62 and its eccentric connection with the driving-shaft. When it is desired to operate all of the pumps, the collar 52 or clutch may be thrown into engagement with the collar 46, when the auxiliary shaft 30 will be caused to rotate and through its connection with the piston-rods of the pumps 59 and 60 they will be operated. If it is desired to pump oil from the reservoir without using the engine-pumps, it is apparent 105 that the hand-pump 123 may be employed and that by moving the piston-rod 126 back and forth oil will be sent through its distributing-pipes to the proper points to be lubricated.

Having thus fully described our invention, what we claim as new, and desire to secure by Letters Patent, is—

1. In a lubricator, the combination with a main frame or casing, of an oil-reservoir 120 mounted thereon, a pump communicating with the reservoir, an engine located within the casing near the reservoir and having a reciprocating piston-rod, a driving-shaft journaled in the lower portion of the casing, an 125 eccentric and adjustable means thereon connecting the piston-rod of the pump with the driving-shaft, a ratchet-wheel fixed on the driving-shaft, a beveled gear loosely mounted on said shaft and carrying a pawl to engage the ratchet-wheel, a shaft journaled on the main frame near the driving-shaft, a beveled gear mounted on said shaft and meshing 130 with the first-named gear, and a crank on the

last-named shaft adjustably connected to the piston-rod of the engine, substantially as described.

2. In a lubricator, the combination with a pump, of an engine having a reciprocating piston-rod, a driving-shaft suitably journaled and connected to the piston-rod of the pump, a ratchet-wheel fixed on said shaft, a beveled gear loosely mounted on the driving-shaft and carrying a pawl to engage the ratchet-wheel, a shaft journaled at a right angle to the driving-shaft, a beveled gear mounted thereon and meshing with the first-named gear, and a crank on said shaft adjustably connected to the piston-rod of the engine, substantially as described.

3. In a lubricator, the combination with a pump, of an engine having a reciprocating piston-rod, a driving-shaft suitably journaled and connected to the piston-rod of the pump, a ratchet-wheel fixed on said shaft, a beveled gear loosely mounted on the driving-shaft and carrying a pawl to engage the ratchet-wheel, a shaft journaled at a right angle to the driving-shaft, a beveled gear mounted thereon and meshing with the first-named gear, a slotted crank on said shaft, a slotted cross-head on the piston-rod of the engine, and a bolt located in the slots of the crank and cross-head and adjustably secured to the latter, substantially as described.

4. In a lubricator, the combination with pumps, of an engine having a reciprocating piston-rod, a driving-shaft and an auxiliary shaft suitably journaled in alinement with one another and connected to the piston-rods of said pumps, a clutch to engage and disengage said shafts, a ratchet-wheel fixed on the driving-shaft, a beveled gear loosely mounted on the driving-shaft and carrying a pawl to engage the ratchet-wheel, a shaft journaled at right angles to the driving-shaft, a beveled gear mounted thereon and meshing with the first-named gear, and a crank on the said shaft adjustably connected to the piston-rod of the engine, substantially as described.

5. In a lubricator, the combination with a pump, of an engine having a reciprocating piston-rod, a driving-shaft suitably journaled and connected to the piston-rod of the pump, a ratchet-wheel fixed on said shaft, a beveled gear loosely mounted on the driving-shaft and carrying a pawl to engage the ratchet-wheel, a graduated plate or casing surrounding the driving-shaft and located over the beveled gear and ratchet-wheel thereon, a pointer secured on the driving-shaft at the face of said plate, a shaft journaled at right angles to the driving-shaft, a beveled gear mounted thereon and meshing with the first-named gear, and a crank on said shaft adjustably connected to the piston-rod of the engine, substantially as described.

6. In a lubricator, the combination with a main frame or casing, of an oil-reservoir mounted thereon, a pump communicating with the reservoir, an engine located within the casing near the reservoir and having a reciprocating piston-rod, a driving-shaft journaled in the lower portion of the casing, an eccentric and adjustable means thereon connecting the piston-rod of the pump with the driving-shaft, a ratchet-wheel fixed on the driving-shaft, a beveled gear loosely mounted on said shaft and carrying a pawl to engage the ratchet-wheel, a graduated plate or casing surrounding the driving-shaft and located over the beveled gear and ratchet-wheel thereon, a pointer secured on the driving-shaft at the face of said plate, a shaft journaled at right angles to the driving-shaft, a beveled gear mounted on said shaft and meshing with the first-named gear, and a crank on the said shaft adjustably connected to the piston-rod of the engine, substantially as described.

7. In a lubricator, the combination with a main frame or casing having in its lower portion a series of oil-wells, a driving-shaft journaled in the casing above said wells, a pump operatively connected to said shaft, an engine having a reciprocating piston-rod, a ratchet-wheel fixed on the driving-shaft, a beveled gear loosely mounted on the driving-shaft and carrying a pawl to engage the ratchet-wheel, a shaft journaled at right angles to the driving-shaft, a beveled gear mounted thereon and meshing with the first-named gear, and a crank on said shaft adjustably connected to the piston-rod of the engine, substantially as described.

8. In a lubricator, a pump comprising a vertical portion having an oil and piston chamber provided with valve-chambers at its top and side, and a horizontal portion provided with an oil-inlet, valve-chamber and channels between said valve-chamber and the valve-chamber at the side of the vertical portion, a piston in said piston-chamber and a ball-valve in each of said valve-chambers, substantially as described.

9. In a lubricator, an oil-pump indicator consisting of a tubular piece having in its upper portion a ball-valve and a hollow extension below said valve provided with a graduated arm, a pointer pivotally secured to said arm, and a piston-rod horizontally located in the hollow extension and provided with enlargement to engage the lower end of the pointer and having on its outer end a knob or thumb-piece, substantially as described.
